(57) CLAIM

The ornamental design for a turkey fan mount, as shown and described.

DESCRIPTION

FIG. 1 is a front perspective view of a turkey fan mount; FIG. 2 is a top front right perspective view of the base of the turkey fan mount shown in FIG. 1, shown separately for clarity of illustration;

FIG. 3 is a bottom front left perspective view thereof; FIG. 4 is a left side elevation view thereof, the right side elevation being a mirror image thereof;

FIG. 5 is a top plan view thereof;

FIG. 6 is a bottom plan view thereof;

FIG. 7 is a rear elevation view thereof;

FIG. 8 is a front elevation view thereof;

FIG. 9 is a slightly enlarged rear right perspective view of the magnetic head component of the turkey fan mount shown in FIG. 1, shown separately for clarity of illustration; FIG. 10 is a left side elevation view of the turkey fan mount of FIG. 1, the right side elevation being a mirror image thereof;

FIG. 11 is a top plan view thereof;

FIG. 12 is a bottom plan view thereof;

FIG. 13 is a rear elevation view thereof; and,

FIG. 14 is a front elevation view thereof.

The broken lines shown in FIGS. 1 and 9-14 illustrate portions of the turkey fan mount that form no part of the claimed design.

1 Claim, 6 Drawing Sheets
